UNITED STATES PATENT OFFICE.

HARRY W. HARDINGE, OF NEW YORK, N. Y., ASSIGNEE TO HARDINGE CONICAL MILL COMPANY, OF NEW YORK, N. Y., A CORPORATION OF NEW YORK.

CONICAL MILL.

1,288,573.

Specification of Letters Patent. Patented Dec. 24, 1918.

Application filed June 29, 1917. Serial No. 177,832.

To all whom it may concern:

Be it known that I, HARRY W. HARDINGE, a citizen of the United States, residing at New York, county and State of New York, have invented certain new and useful Improvements in Conical Mills, of which the following is a full, clear, and exact description.

The invention which constitutes the subject matter of this application relates to an improvement in conical mills the latter consisting, in its most common form, of cones arranged base to base (preferably with a cylindrical section between the two) and having an inlet opening at the apex of one cone and an outlet opening, at the apex of the other. It is with a mill of this type that my improvements are incorporated.

Figure 1 illustrates a longitudinal section 20 of a conical mill.

Fig. 2 is a section taken on line 2--2 of Fig. 1.

The distinguishing structural characteristic of all conical mills is the tapering shape 25 of the portion (which may be conveniently referred to as the outlet portion) next to the axial outlet opening. This tapering form causes the material in the outlet portion to assume a sort of vertical stratification according to size, the largest pieces being at 30 the plane of greatest diameter and the pieces diminishing in size toward the outlet, as fully described in my Patent No. 908,861.

In most cases the assorting of the material 35 according to size, produced by the tapered form of the outlet portion, permits only particles of the desired degree of fineness to issue from the outlet under normal load, but in working with capacities above normal, as 40 is often desirable to increase capacity of a single mill, it is found that some of the material discharged is composed of particles which are too large for the purpose desired. In such cases it is necessary to separate the 45 coarse uncrushed material and return it to the same mill, or to another mill, for re-grinding. The present invention relates to this problem, and its object is to provide means whereby the desired separation will 50 be effected inside of the mill and the coarse particles retained in the mill for further reduction, instead of permitting them to pass out as would be the case without the screen. Hence it is economically desirable to provide 55 means for the purpose which shall be simple

in character and effective in operation, and which can be easily and cheaply applied.

In operating conical mills for a number of years I have observed that the difference in diameters and consequent difference in peripheral speeds at different portions of the cones has the distinctive feature of drawing or massing the contents (when in operation) toward the greatest diameter. This result ensues to an extent that when the mill is 65 filled to its center with grinders and material being ground, the inlet and outlet trunnions are practically closed to the admission of more material, yet when the mill is rotated the above mentioned material tends to 70 draw away from the cones to the center of the mill, piling up at its greatest diameter, leaving more or less free spaces below the axis, as shown at "a". This free space due to segregating of material does not occur in a 75 cylindrical mill in which the peripheral speed is the same throughout its whole length, except perhaps when the mill is fed below the desired maximum capacity, at which time, of course, the necessity for any 80 screen does not exist.

I also take advantage of the fact that there is thus in a screened cone a much larger free screen area, as illustrated above the coarse mass of grinding mediums and material being ground, and a smaller area of screen is thus subjected to wear than in a mill where the screen is the full diameter of the mill. In the latter case there is an excessive and unnecessary wear of the screen 85 and consequent consumption of power in action upon a partially closed and practically inoperative section.

The screen in a cone is not required to retain as great a quantity of large unground 90 material or grinding mediums against its surface owing to the classifying action of the cone, hence the screen area for equal volumes of material passing through the mill is less than its average diameter and 95 more nearly adjusted to exact requirements.

Referring specifically to the drawing, reference numeral 10 designates the inlet portion of a conical mill, 11 the outlet portion, and 12 the cylindrical portion between 105 the conical portions. The mill is also provided, among other things, with the trunnions 13 at the apex of the cone 10, and 14 at the apex of the cone 11. Any suitable bearings 15 and 16 may be provided so as 110

to enable it to rotate about its longitudinal axis, and any suitable mechanism may be employed to effect said rotation, such as the gear indicated. A convenient and effective means for preventing large pieces or bits of material from escaping along with material of the desired degree of fineness is illustrated at 17 and comprises a screen inside the conical outlet portion of the mill. A screen located in the cone of a grinding mill has the advantage of a comparatively unobstructed area of the screen and obviates the excessive grinding area on the screen by the balls and grinding mediums. The object of this screen is to retain within the mill the material being ground until it is of a size which will pass through the meshes or orifices of the screen. This screen or barrier may be provided with a central orifice or opening 18 of sufficient size to pass material substantially or approximately as large as that originally fed to the mill, this opening acting as a safety or overflow opening to prevent choking of the mill with the material undergoing disintegration. The exact location of the screen within the conical portion 11 for best results is dependent upon the size and character of the material being ground. If the material being ground is coarse then the screen should be placed more or less adjacent to the base of the conical portion. If, however, the material being ground is not so coarse the screen should be arranged nearer the apex of the cone. For ordinary requirements the screen is preferably located midway between the apex and base of the cone.

The material after passing the screen may be removed by any well known means, preferably by the lifting vanes 19. This keeps the material removed on the outlet side so as to insure free passage of the finer material through the screen. It will therefore be

seen that the screen back of the outlet defines two chambers, one for the unscreened 45 and the other for the screened material.

What I claim is:

1. The combination with a grinding mill of the kind described having a conical outlet portion, of a screen secured to the walls 50 of said conical portion of the body of said mill within the same and back of the outlet thereby forming a chamber therein on each side of said screen, one of which is adapted to receive the screened material, and means 55 for removing the material after passing the screen so as to provide a hydrostatic or gravity head on the free side of the screen whereby a free flow of the material through the screen is provided.

2. The combination with a grinding mill of the class described having an inlet opening and a conical outlet portion, of a screen within the walls of said conical portion of the body of said mill, the meshes or perforations of which extend not only to a point below the axis of the mill but also to a point 60 below the inlet opening, and means within said mill for removing the material as fast as it passes through the screen, whereby an unrestricted free flow of the material through the screen is provided.

3. A grinding mill of the class described comprising an inlet opening, a conical outlet portion, a screen within the walls of said 75 conical portion of the body of said mill, the meshes or perforations of which extend not only to a point below the axis of the mill but also to a point below the inlet opening, whereby the screen is adapted to permit a 80 free flow of the crushed or ground material therethrough.

In testimony whereof I hereunto affix my signature.

HARRY W. HARDINGE.
